John C. Martin Inventor

By Jerry A. Mathews

Attorney

UNITED STATES PATENT OFFICE.

JOHN C. MARTIN, OF TERRE HAUTE, INDIANA.

DEPOSIT AND COLLECTION RECEPTACLE.

Application filed March 15, 1923. Serial No. 625,323.

To all whom it may concern:

Be it known that I, JOHN C. MARTIN, a citizen of the United States, residing at Terre Haute, in the county of Vigo and State of Indiana, have invented certain new and useful Improvements in Deposit and Collection Receptacles, of which the following is a specification.

My invention relates to deposit and collection receptacles.

An important object of the invention is to provide a device of the above mentioned character, which is adapted for use in connection with milk bottles, while not necessarily restricted to this use, and so constructed that the owner of the device may lock the opening element against effective movement, while the closing element is free to be operated by the milkman or the like, whereby the bottle of milk may be placed into the device, the door closed, and the closing element shifted to the active position by the milkman, whereby the door is securely locked in the closed position, against opening movement by an unauthorized person.

A further object of the invention is to provide a device of the above mentioned character, which is of simple construction, convenient in use, and reliable in operation.

Other objects and advantages of the invention will be apparent during the course of the following description.

In the accompanying drawings, forming a part of this specification, and in which like numerals are employed to designate like parts throughout the same,

Figure 1 is a side elevation of the front side of the device.

Figure 2 is an end elevation of the same, Figure 3 is a side elevation of the inner side of the door,

Figure 4 is a transverse section taken on line 4-4 of Figure 3,

Figure 5 is an edge elevation of the bolt closing element, and,

Figure 6 is a detail section taken on line 6-6 of Figure 4.

In the drawings, wherein for the purpose of illustration is shown a preferred embodiment of my invention, the device embodies a casing or shell 10, preferably formed of sheet metal. This casing is preferably entirely closed excepting for its front side or face, which is adapted to be covered by a door 11, hinged to the casing at its up-

per end, as shown at 12. The inward movement of the door 11 is limited by a stop or flange 13, preferably formed by bending the material of the bottom of the shell inwardly and upwardly, as shown in Figure 4. The flange 13 also serves as a keeper for the bolt to be described.

Secured to the inner side of the door 11 by means of rivets 14 or the like, is a plate 15, carrying elements of the lock. This lock embodies a preferably vertically arranged bolt 16, slideable within guides 17, which are rigidly attached to the inner side of the plate 15. The lower end of the bolt 16 is inwardly offset, as shown at 18, to engage inwardly of or behind the flange or keeper 13, as more clearly shown in Figure 4. At its upper end, the bolt 16 is provided with an inwardly projecting lateral extension 19, preferably formed integral therewith.

The numeral 20 designates a curved or bowed leaf spring, extending through an eye 21 carried by the bolt 16. The ends of this curved spring are held loosely within sockets 22, formed upon plates 23, which are in turn attached to the inner side of the plate 15. The function of this curved spring is to hold the bolt 16 in its retracted or projected positions, when shifted thereto, and also to aid in moving the same to these positions, when the bolt has been moved longitudinally in either direction, sufficiently, to bring the intermediate portion of the spring past dead center.

The numeral 24 designates a bolt closing element, preferably in the form of a flat arm, arranged upon the inner side of the plate 15. This arm is provided near one end with an opening 25 which is square in cross section, for receiving the end of a reduced extension 26, which end is also square in cross section. The arm 24 is held upon the extension 26 by means of a machine screw 27 or the like. The reduced extension 26 is cylindrical and is rotatable within an opening formed in the door 11, and is formed integral with a spindle 28, forming therewith a shoulder 29. This spindle is disposed upon the exterior of the door and carries a transverse pin or grip 29, by means of which the spindle may be manually turned. The inner end of the arm 24 is preferably offset laterally slightly and is enlarged to provide a rectangular portion 30, having the words "Open" and "Closed," formed upon its outer face, which words

are adapted to be visible through an opening 32 formed in the door, Figure 1. The forward end of the arm 24 is positioned over the lateral extension 19 of the bolt, and 5 is adapted to contact therewith, while the upward movement of the arm 24 is limited by a stop 33, as shown. It is thus seen that with the bolt 16 raised, as shown in Figure 3, the door 11 may be opened, but when this 10 door is in the closed position, and the spindle 28 turned in a direction to swing the arm 24 downwardly, the bolt 16 will be projected to the closed position, whereby it will engage behind the keeper or flange 13 15 and the door will be locked in the closed position. The forward movement of the arm 24 cannot move the bolt upwardly.

The numeral 34 designates a manually operated bolt opening element, preferably in 20 the form of a lever formed of flat sheet metal. This element or lever is pivoted at 35, upon a bracket 36, suitably attached to the forward side of the door, as shown. The element or lever has an extension or 25 end portion 37, operating through a longitudinal slot 38, formed through the door and the plate 15. This extension also projects through a longitudinal slot 39, formed in the bolt 16. The upward movement of 30 the outer end of the element or lever 34 is limited by means of a stop 40, and hence this element cannot be employed in shifting the bolt to the closed position. When the bolt is projected downwardly to the 35 closed position. The upper end wall 41 of the slot 39 will be arranged above and slightly spaced from the cam surface 42 of the element 34, and if this element 34 is capable of having its outer end moved 40 downwardly for its full extent of movement, the element 34 will be capable of raising or retracting the bolt to its open position. The movement of the element 34 is controlled by a lock 43, preferably a pad 45 lock, having its hasp 44 adapted to be inserted through an opening 45 in the element 34, and a corresponding opening in the bracket 36. The size of these openings is such that the element 34 can only partake 50 of a limited movement, and not sufficient to bring the cam face 42 into contact with the end wall 41, when the bolt 16 is in the closed position. However, when the pad lock is removed from the element 34, the 55 outer end of this element or lever may be swung downwardly throughout its full extent of movement, and the cam face 43 will then engage the end wall 41 and shift the bolt 16 to the upper or open position, thereby releasing the door 11 so that it may be 60 opened.

In the use of the device, the collector places the lock 43 upon the element or lever 34 and bracket 36, and locks the same thereon, thereby limiting the effective movement 65

of this element or lever, upon its pivot. The door 11 may be left opened or closed, as desired. The depositor then places the bottle of milk or the like within the casing 10 and closes the door, and then turns 70 the spindle 28 in the proper direction, for shifting the closing element 24 downwardly. This element shifts the bolt 16 downwardly so that it engages behind the keeper or flange 13. The door is now locked in the 75 closed position, and cannot be opened, until the pad lock 43 is removed from the opening element or lever 34, whereby this lever may be moved downwardly throughout its 80 entire extent of travel, as explained.

It is to be understood that the form of my invention herewith shown and described is to be taken as a preferred embodiment of my invention, and that various changes in the shape, size, and arrangement of parts, may be resorted to without departing from the spirit of my invention, or the scope of the subjoined claims.

Having thus described my invention, I claim:

1. In a deposit and collection device, a casing, a door controlling access to the interior of the casing, a movable bolt carried by the door, a manually operated closing element adapted to engage the bolt and shift it to the closed position, a manually operated opening element adapted to engage the bolt and shift the same to the open position and incapable of shifting the same to the closed position, and a lock engaging 95 the manually operated opening element to normally prevent such element from moving sufficiently to actuate the bolt.

2. In a deposit and collection device, a casing, a door controlling access to the interior of the casing, a sliding bolt carried by the door, a pivoted bolt closing element carried by the door to engage the bolt and shift the same to the closed position and being incapable of shifting the bolt to the open position, manually operated means arranged exteriorly of the door to move the pivoted bolt closing element, a pivoted bolt opening element adapted to engage the bolt and shift it to the open position and being incapable of shifting the bolt to the closed position, said bolt opening element being operable from the exterior of the door, and lock means arranged exteriorly of the door for regulating the extent of movement of the bolt opening element.

3. In a deposit and collection device, a casing, a door controlling access to the interior of the casing, a sliding bolt carried by the door, spring means to hold the bolt in the opened and closed positions when shifted thereto, a pivoted bolt closing element carried by the door and engaging the bolt and adapted to shift the same to the 125 130

closed position and incapable of shifting the same to the open position, manually operated means to move the pivoted element, a bolt opening element pivoted upon the door and adapted to shift the bolt to the open position and being incapable of shifting the bolt to the closed position, said bolt opening element being operable from the exterior of the door, and lock means arranged exteriorly of the door to regulate the extent of movement of the bolt opening element.

5

10

15

door and extending transversely of the bolt and having connection therewith and holding the bolt in the opened or closed position when shifted thereto, a manually operated element engaging the bolt to shift it to the closed position and incapable of shifting it to the opened position, a manually operated element engaging the bolt to shift it to the open position and incapable of shifting it to the closed position, and lock means controlling the extent of movement of the second named manually operated element.

20

25

In testimony whereof I affix my signature.

JOHN C. MARTIN.

4. In a deposit and collection device, a casing, a door controlling access to the interior of the same, a sliding bolt carried by the door, a curved leaf spring carried by the
